(57) **CLAIM**

The ornamental design for a vertical trifold cell phone wallet, as shown and described.

DESCRIPTION

FIG. 1 is a perspective view of a vertical trifold cell phone wallet according to an embodiment showing my new design; FIG. 2 is a front view thereof;

FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a perspective view of the vertical trifold cell phone wallet in an open condition;
FIG. 9 is a front view thereof;
FIG. 10 is a rear view thereof;
FIG. 11 is a left side view thereof;
FIG. 12 is a right side view thereof;
FIG. 13 is a top view thereof;
FIG. 14 is a bottom view thereof;
FIG. 15 is a perspective view of the vertical trifold cell phone wallet in a stand configuration;
FIG. 16 is a front view thereof;
FIG. 17 is a rear view thereof;
FIG. 18 is a left side view thereof;
FIG. 19 is a right side view thereof;
FIG. 20 is a top view thereof; and,
FIG. 21 is a bottom view thereof.

The present application is directed to the design illustrated in the drawings. The broken lines showing portions of the cell phone wallet are for purposes of illustrating environment and forms no part of the claimed design.

1 Claim, 15 Drawing Sheets

Related U.S. Application Data

a continuation of application No. 29/519,837, filed on Mar. 9, 2015, now Pat. No. Des. 755,513, which is a continuation of application No. 29/449,467, filed on Mar. 15, 2013, now Pat. No. Des. 727,619.
